(57) **CLAIM**

The ornamental design for a corner stand, as shown and described.

DESCRIPTION

FIG. 1 is a perspective view of the corner stand showing our new design;

FIG. 2 is a front view thereof;

FIG. 3 is a right side view thereof, the left side being a mirror image thereof;

FIG. 4 is a rear view thereof;

FIG. 5 is a top view thereof;

FIG. 6 is a bottom view thereof;

FIG. 7 is a perspective view of another embodiment of the corner stand according to the present invention;

FIG. 8 is a front view of the corner stand of FIG. 7;

FIG. 9 is a right side view of the corner stand of FIG. 7, the left side being a mirror image thereof;

FIG. 10 is a rear view of the corner stand of FIG. 7;

FIG. 11 is a top view of the corner stand of FIG. 7; and,

FIG. 12 is a bottom view of the corner stand of FIG. 7.
